PROCESS FOR PRODUCING NITROGEN
TRICHLORIDE

Erich Staudt, Deventer, Netherlands, assignor to
Naamlooze Vennootschap Industriële Maatschappij Voorheen Noury & Van Der Lande,
Deventer, Netherlands, a company of the
Netherlands

Application June 22, 1937, Serial No. 149,787
In the Netherlands June 30, 1936

7 Claims. (Cl. 204—9)

In my copending application Serial No. 51,714, filed November 26, 1935, now Patent No. 2,118,903 granted May 31, 1938, the preparation of nitrogen trichloride by the electrolysis of an acidified solution containing ammonium and chloride ions has been described. In said application, it has been disclosed that by the electrolysis of water solutions of ammonium chloride, or other water solutions containing ammonium and chloride ions, which have been given an acid reaction by the addition of acid, the production of nitrogen trichloride is favored and that the yield of nitrogen trichloride from the electrolysis of said acidified solutions increases as the acidity of the solution increases. It has also been disclosed in said application that hydrochloric acid, as well as other acids, may be added to the ammonium chloride solution, or other solution containing ammonium and chloride ions, to impart to the said solutions an acid reaction, and that the quantity of hydrochloric acid or other acid that is used per gram-molecule of ammonium chloride may fluctuate between broad limits, e. g., both with one-tenth and 2 gram-equivalents of acid per gram-molecule of ammonium chloride, good results have been obtained. During the electrolysis of said acid reacting solutions containing ammonium and chloride ions, nitrogen trichloride is removed from the electrolyte by passing or blowing air or other gas through the electrolyte in the cell during electrolysis, or suction or vacuum is applied to the cell to produce a low or decreased pressure of gas over the electrolyte whereby, in the latter instance also, the nitrogen trichloride is caused to escape from the electrolyte and enters the gases which are sucked or aspirated from the cell by the suction apparatus or other apparatus producing the vacuum or partial vacuum. The nitrogen trichloride prepared in this way can be used with advantage for improving the color and the baking quality of flour, as well as for maturing flour. The devices and apparatuses for the preparation of nitrogen trichloride in the electrolytic way described must accordingly be mounted in flour mills when the nitrogen trichloride is used for the treatment of flour. Since the production of flour is, as a rule, a continuous process, the electrochemical preparation of nitrogen trichloride for the treatment of flour should preferably take place in such a way that it can be continued for a long period of time without interruption and without supervision and attendance being necessary.

In applying the process described in my above mentioned patent application, it appeared to be

necessary to add a new or additional portion of acid from time to time to the electrolyte in order to maintain the acid reaction of the electrolyte, since the electrochemical process of preparing the nitrogen trichloride apparently took place with consumption of acid. However, handling acids and especially strong acids is extremely inconvenient in works or plants, such as flour mills, that are not equipped for handling acids. Moreover, it was of course a drawback of the said process that a constant control of the degree of acidity of the electrolyte was necessary, since there was the danger that by omitting a timely addition of acid, the degree of acidity of the electrolyte would fall too much, so that even an alkaline reaction could arise, through which the production of nitrogen trichloride would be decreased to a very considerable extent and finally would practically cease altogether.

That the danger is not excluded that the reaction of the electrolyte may really become an alkaline one, if care is not taken for a timely addition of acid, appears from the following table giving the results of the determinations of acid in an electrolyte that in the beginning of the experiment contained per one litre of water solution (electrolyte) 150 grams of ammonium chloride and 24 grams of hydrochloric acid (HCl). The electrolysis was carried out with a current strength of 1.6 amp. at a tension of 3-3.5 volts. The alterations in the degree of acidity of the electrolyte were as follows:

Time of electrolysis, hours	Grams of hydrochloric acid per 100 ccms. of electrolyte
0.....	2.40
8 $\frac{1}{2}$	1.81
15 $\frac{1}{2}$	1.29
20.....	0.98
28.....	0.50
32.....	0.02
34.....	Alkaline

It was now found that it is possible to keep the acidity of the water solution of ammonium chloride, or other aqueous solution containing ammonium and chloride ions, constant or approximately constant in producing nitrogen trichloride electrolytically according to the process described in my said application, by allowing a part of the nitrogen trichloride formed to undergo, in the electrolyte in the cell, a reaction of decomposition which yields acid in greater proportion than the proportion of acid consumed in the electrolytic preparation of the nitrogen trichloride. In this

manner it becomes possible to practice the process described in my said application continuously for long periods of time, with a constant or nearly constant acidity, without extraneous addition of hydrochloric acid or other acid, by so adjusting or regulating the amount of nitrogen trichloride that is allowed to decompose with the formation of acid that the amount of acid resulting from such decomposition of nitrogen trichloride will 10 compensate or equal exactly or approximately the amount of acid consumed in the electrolysis of the acid reacting aqueous solution containing ammonium and chloride ions which yields the nitrogen trichloride.

15 A continued search showed that the chemical reaction causing the desired formation of acid, and taking place without violent phenomena, is probably the following:

20 Now according to the process of the present invention measures are taken, in accordance with the above mentioned chemical reaction, to let the said acid forming reaction take place to the desired extent, so that the degree of acidity of the electrolyte remains constant or nearly constant.

30 It appeared that the above mentioned reaction is influenced by various circumstances, so that it is to be considered that the extent to which the reaction takes place is determined by more than one factor.

35 In the first place, the concentration of the ammonium ions is of importance and this concentration must be as high as possible in order to let the reaction take place to the right. Thus, according to the process of the present invention, one preferably uses a concentrated ammonium chloride solution as the electrolyte, for 40 example, a water solution of ammonium chloride containing 100 grams of ammonium chloride per litre, but the upper limit of the concentration is fixed by the solubility of ammonium chloride under the circumstances prevailing in the electrolyte. It is clear that the ammonium chloride in the electrolyte may be wholly or partly substituted by another ammonium salt, provided that a sufficiently high chloride ion concentration is provided in some other way.

50 It is further advisable to practice the process of the present invention at a temperature which is not too low, since the solubility of ammonium chloride increases with rising temperature. Suitable temperatures lie, for example, between 15 and 35° C. If necessary the electrolyte is kept at the right temperature by heating or cooling.

60 A further measure that may be taken in order to attain the object contemplated by the present invention is the provision of a large volume of electrolyte. In this case the nitrogen trichloride that is present in the electrolyte in a dissolved state and in the form of gas bubbles finds an opportunity to reach the required degree of decomposition prior to escaping from the electrolyte 65 as a gas. It appears that the best measure for the volume of electrolyte is the volume of electrolyte per square centimeter of active electrode surface.

70 Dependent on the material that is used for the electrodes this volume may lie at various values. Thus in case of graphite and carbon electrodes 5-100 ccms. of electrolyte is the volume per square centimeter of active surface of electrodes; and in case of platinum electrodes, the volume is 75 100-2000 ccms. per square centimeter of active

electrode surface. By active surface of electrodes is meant the total surface of both positive and negative electrodes that is taking part in the charging and discharging of ions during electrolysis.

5 Another manner of influencing the degree of decomposition of the nitrogen trichloride according to the present invention, and accordingly for increasing the amount of available acid in the electrolyte, consists in the appropriate choice of 10 the quantity of air or of the other gas that is blown through the electrolyte during the electrolysis according to my above mentioned application in order to eliminate the nitrogen trichloride formed.

15 The influence of the quantity of air is such that in case of a too small supply of air, the degree of acidity of the electrolyte will rise because the period of contact of the nitrogen trichloride with the electrolyte is too long in this case. If, on the contrary, the quantity of air is too large the time of contact of the nitrogen trichloride with the electrolyte will be too small and the degree of acidity of the electrolyte will fall. It was found that per 100 litres of electrolyte a current of 25 30-300 litres of air or other gas (measured at 15° C. and 760 mm. pressure) per minute gives the best results. It is, however, necessary to determine by some preliminary tests what quantity of air or other gas must be used in a certain case.

20 Besides the quantity of air or other gas that is passed through the electrolyte during electrolysis, the direction of movement of the air or gas in the electrolyte is of importance. The air may be given such a movement through the electrolyzing cell or electrolyte that the nitrogen trichloride formed remains in contact with the electrolyte for the required time prior to escaping. By this contact the above mentioned reaction of decomposition may take place to the desired extent.

25 As in the process described in my above mentioned application, the air or other gas used according to the present invention serves also as a means for eliminating the nitrogen trichloride 30 formed from the electrolyte and as a stirring agent for keeping the composition of the electrolyte uniform. The stirring movement of the air or other gas may be made such by an appropriate choice of the method of introduction, 35 that the nitrogen trichloride formed at the electrodes, prior to leaving the liquid, is carried away by the current of air and is further brought into contact with the electrolyte. Various possibilities exist for carrying out the above described 40 form of stirring movement, some of which, by way of example, are illustrated in the accompanying drawings, in which Figures 1, 2 and 4 respectively represent vertical cross sections of three different electrolyzing cells and Figure 3 represents a top plan view of another electrolyzing cell. According to Figure 1, for example, the air or gas may be blown into the electrolytic cell container 1 at the bottom, in the neighborhood of the sidewalls, through perforated pipes 2 and 3, 45 and the electrodes 4 and 5 may be mounted in the middle of the cell between the two air supply pipes 2 and 3. In this way the air or other gas sets the liquid in a double rotating movement as is indicated by the broken lines 6 and arrow heads 7.

50 It is further possible to choose the place for introducing the air in the middle of the electrolytic cell, and to mount the electrodes along the sides as shown in Figure 2. Referring to said 75

figure, the numeral 11 indicates the container of the electrolytic cell. The air is blown into the cell at the bottom, near or at the middle, through a perforated pipe 12, and two sets of electrodes 14 and 15 may be employed, one set being positioned near one side of the electrolytic cell and the other set being positioned near the opposite side of the electrolytic cell. The air or gas introduced causes the contents of the cell to be circulated as indicated by the broken lines 16 and arrow heads 17. As is indicated in Figure 2, in this case also the nitrogen trichloride formed at the electrodes is brought into contact with the electrolyte by the air or other gas.

Figure 3 illustrates another manner of carrying out the process according to which the electrolyte is given a horizontal rotating movement in a cell container 21, owing to a sidelong supply of air from perforated pipe 22. This rotating movement of the electrolyte also causes the desired contact of nitrogen trichloride with the electrolyte. The electrodes in Figure 3 are designated by the numerals 24 and 25, and the movement of the liquid contents of the cell is indicated by broken line 26 and arrow heads 27.

It is to be understood that mechanical stirrers may be used to obtain the stirring or circulation of the contents of the electrolytic cell, although of course this is less advisable from a construction or operating point of view than using the current of air in the way described, especially since the air is blown through the electrolyte for removing nitrogen trichloride and for maintaining the body of the electrolyte uniform during electrolysis.

By mounting partition walls, edges, grooves and the like in the electrolytic cell, the movement of air in the liquid may be caused to take place in the desired manner, and the shape of the electrolyzing cell may be chosen to contribute to obtaining the desired movement of air or electrolyte. This manner of practicing the invention is illustrated in Figure 4. The cell container 31 is divided into two compartments of substantially equal volume by means of the partition 38, below which is positioned the perforated pipe 32 from which air is discharged along each side of the partition. Two sets of electrodes 34 and 35 are provided, one set being placed near one side of the cell container and the other set being placed near the opposite side of the cell container, there being one set of electrodes, as shown in the drawing, in each compartment of the cell. The air introduced from pipe 32 causes the contents of each compartment of the cell to be circulated as indicated by the broken lines 36 and arrow heads 37.

A combination of the various methods for moving the liquid in the electrolytic cell with one or more of the other measures described above may be used, if only care is taken that the nitrogen trichloride formed is brought into contact with the electrolyte in such a way that a degree of decomposition takes place at which the degree of acidity of the electrolyte remains constant or nearly constant. It is also to be understood that two or more or all of the above described measures for promoting the decomposition of nitrogen trichloride may be used at the same time in connection with the same electrolytic cell for compensating for losses of acid during the production of nitrogen trichloride as described in my above mentioned application for patent.

Preliminary tests are necessary to determine

to what extent and in what way the measures described above must be applied in each case, since the effect cannot always exactly be calculated in advance. The various measures influencing the decomposition of the nitrogen trichloride supplement each other's action but not in such a way that a simple computation of their combined effect is possible. With each cell construction, in which also the shape of the cell and its dimensions play a part, some preliminary tests under control of the degree of acidity of the electrolyte must be performed in order to determine to what extent the said measures are to be taken so that an arrangement of said measures is reached which results in a constant or nearly constant degree of acidity of the electrolyte. If the electrolysis is continued in this arrangement, the degree of acidity of the electrolyte will automatically remain at the same value.

It will be seen from the foregoing that an aqueous solution of acid reaction containing ammonium ions and chloride ions is subjected to electrolysis to yield nitrogen trichloride; that nitrogen trichloride is removed from the said solution during electrolysis thereof, for example, by passing air through said solution during electrolysis thereof; that the acidity of the said solution is maintained constant or approximately constant during the electrolysis thereof by leaving enough of the nitrogen trichloride produced by the electrolysis in contact with the said solution for a sufficient period of time to react with it to form a sufficient amount of acid to equal or compensate or to approximately equal or compensate the amount of acid which is consumed in the electrolysis. In this manner, the loss or consumption of acid produced by the electrolytic action may be compensated or equalled, or even exceeded, according to the amount of nitrogen trichloride that is allowed to be decomposed by the electrolyte with the formation of acid. While the initial acid condition of the electrolyte or solution electrolyzed may be produced by the addition of acid to the electrolyte, it is to be understood that this initial condition may be brought about in any other suitable way, for example the initial acid condition may be produced by allowing nitrogen trichloride to react with an electrolyte containing ammonium chloride or ammonium and chloride ions.

I claim:

1. In the art of producing nitrogen trichloride wherein an aqueous solution containing ammonium and chloride ions and free acid is electrolyzed, and nitrogen trichloride is removed from the solution, the process which comprises removing only a part of the electrolytically produced nitrogen trichloride from the solution and contacting the remaining part of the electrolytically produced nitrogen trichloride with the solution for sufficient time to be decomposed thereby with the production of acid, the extent of said removal of nitrogen trichloride being such that the said remaining part of nitrogen trichloride so decomposed is sufficient in amount to yield at least enough acid to equal the amount of free acid consumed in the electrolysis.

2. In the art of producing nitrogen trichloride wherein an aqueous solution containing ammonium and chloride ions and free acid is electrolyzed, and nitrogen trichloride is removed from the solution by passage of a gas through the solution, the process which comprises removing only a part of the electrolytically produced ni-

trogen trichloride from the solution by said gas and contacting the remaining part of the electrolytically produced nitrogen trichloride with the solution for sufficient time to be decomposed thereby with the production of acid, the extent of said removal of nitrogen trichloride being such that the said remaining part of nitrogen trichloride so decomposed is sufficient in amount to yield enough acid to maintain the free acid content of the solution about constant.

3. In the art of producing nitrogen trichloride by the electrolysis of an aqueous solution containing ammonium and chloride ions and free acid and in which a carrier gas for nitrogen trichloride is passed through the solution during the electrolysis, the process which comprises maintaining the free acid content of the said solution during said electrolysis about constant by conducting the carrier gas through the said solution during electrolysis at a rate of 30 to 300 liters per minute per 100 liters of solution undergoing electrolysis.

4. Process for producing nitrogen trichloride which comprises electrolyzing an aqueous solution containing ammonium and chloride ions in the presence of free acid which imparts to the solution an acidity greater than the acidity of solutions consisting of ammonium chloride dissolved in water, and conducting a gas through the solution during the electrolysis thereof to remove nitrogen trichloride, said gas being of such a

nature that in its passage through the solution nitrogen trichloride is carried out of the solution by said gas, the manner of conducting said gas through said solution and the rate of its passage through the solution being such that sufficient part of the nitrogen trichloride produced in the electrolysis is contacted for sufficient time for reaction with said solution for the production of acid that the acid thereby resulting at least equals in amount the acid consumed in the electrolysis, the remaining portion of the nitrogen trichloride which has not undergone reaction with said solution being carried away by said gas.

5. Process according to claim 2 in which the volume of the aqueous solution electrolyzed is at least 5 cubic centimeters per square centimeter of active surface of electrodes.

6. Process according to claim 2 in which carbon electrodes are employed in the electrolysis of the aqueous solution, and in which the volume of the aqueous solution is 5 to 100 cubic centimeters per square centimeter of active surface of electrodes.

7. Process according to claim 2 in which platinum electrodes are employed in the electrolysis of the aqueous solution, and in which the volume of the aqueous solution is 100 to 2000 cubic centimeters per square centimeter of active surface of electrodes.
